UNITED STATES PATENT OFFICE.

FRANK ZOLDO, OF NEW YORK, N. Y.

DESIGN FOR JEWELRY—NAMELY, A FINGER-RING OR ARTICLE OF SIMILAR NATURE.

56,402.

Specification for Design.

Patented Oct. 5, 1920.

Application filed June 26, 1920. Serial No. 392,113. Term of patent 3½ years.

To all whom it may concern:

Be it known that I, FRANK ZOLDO, a citizen of the United States, residing at New York City, in the county and State of New York, have invented a new, original, and ornamental Design for Jewelry—namely, a finger-ring, or article of similar nature—of which the following is a specification, reference being had to the accompanying drawing, forming a part thereof.

Fig. 2 is a side elevational view of a finger ring showing my new design.

Fig. 3 is a top or plan view of a finger ring showing my new design.

I claim:

The ornamental design for jewelry, namely a finger ring, or article of similar nature, as shown.

In testimony whereof I affix my signature.

FRANK ZOLDO.
